UNITED STATES PATENT OFFICE.

JULES E. REBOURS, OF GRAND RAPIDS, MICHIGAN.

CAMPING TRUNK.

Application filed December 29, 1924. Serial No. 758,754.

To all whom it may concern:

Be it known that I, JULES E. REBOURS, a citizen of the United States of America, residing at Grand Rapids, in the county of

5 Kent and State of Michigan, have invented certain new and useful Improvements in Camping Trunks; and I do hereby declare the following to be a full, clear, and exact description of the invention, such as will enable others skilled in the art to which it ap-

10 pertains to make and use the same.

This invention relates to improvements in camping trunks particularly adapted to be used with automobiles and it deals particu- 15 larly with the type of trunk which may be dismembered and the separate parts such as the top, front and ends utilized to form articles of camp furniture such as a table and benches.

20 The invention pertains especially to the construction of the device which is so arranged that the various parts may be quickly and easily put together or taken apart and may be rigidly locked when assembled

25 so that it will be impossible to gain access to the interior without the proper key to fit the locks. The joints between the members are so constructed that a tight connection will be formed which will exclude moisture

30 and dust and will prevent the members from rattling. Novel interlocking means are pro- vided and are so arranged that they may be conveniently actuated and no parts are per-

35 mitted to project from the members in places where they would interfere with the use of said members as articles of furniture.

The various parts of the trunk are provided with legs and drawers conveniently located and arranged to fold when not in use and to 40 support the parts as pieces of furniture and the device is provided with various other novel features of construction and arrangement which will more fully appear as a clear understanding of the structure is had from

45 the following description, reference being had to the accompanying drawings in which:

Fig. 1 is a perspective view of a trunk embodying this invention shown in assem- 50 bled or closed arrangement.

Fig. 2 is a perspective view of the back and bottom of the trunk with the other parts removed.

55 Fig. 3 is a perspective view of one of the end members showing the legs attached thereto folded.

Fig. 4 is a perspective view of the front, top and one end supported by their legs in position to be used as a table, bench, and stool, respectively. 60

Fig. 5 is a transverse sectional elevation of the device in assembled condition.

Fig. 6 is a longitudinal sectional elevation of one end of the same, the section being taken substantially through the center of the 65 device.

Fig. 7 is a sectional plan of one end of the same.

Fig. 8 is an enlarged fragmentary section showing the means utilized to join the top 70 with any of the vertical members.

Fig. 9 is an enlarged fragmentary section showing details of the means of joining the bottom with the front, and end members.

Fig. 10 is an enlarged fragmentary sec- 75 tion showing a modified means of joining the top with the vertical members, and

Fig. 11 is an enlarged fragmentary section showing a modified means of joining the bottom with the vertical members. 80

Like reference numerals apply to like parts in all of the figures.

The trunk is composed essentially of a bottom 1, back 2, top 3, front 4, and two end members 5. The back and bottom are 85 preferably permanently joined although it would be possible to have these two members separable so that they might be utilized as articles of furniture if so desired. The top, front, and ends are adapted to form respec- 90 tively a bench, table, and stools and are separable from the back and bottom and also from each other. The top 3 is provided with folding legs 6, the front 4 is provided with folding legs 7, and the ends 5 are pro- 95 vided with folding legs 8, which, when ex- tended, support the members so that they may be used as articles of furniture and when folded they will lie close to the inner surfaces of the members thereby enabling 100 the members to be assembled to form the trunk with considerable space inside it for the storage and transportation of articles such as suit cases, camping equipment or the like. The front 4 which forms the table 105 is also provided with drawers 9 which are mounted to slide and when moved inward are arranged to fit between the legs 7 when the legs are folded. The legs 8 of the end members 5 or stools are hinged in such a 110 way that they will not readily unfold when the trunk is assembled. Each pair of legs

is connected by a cross brace 10 and when the member is arranged in position to be assembled in the trunk the legs which fold upward are behind the cross brace 10 of the 5 legs which fold downward. The weight of the legs which fold downward will prevent the upward folding legs from unfolding, the cross brace 10 acting as a retainer to hold them in place.

- 10 As a means of joining the members a channel 11 extends completely around the top 3 or bench member and opens downwardly. A similar channel 12 extends across the ends and front of the bottom member opening upward and a continuation 13 of this channel extends along the vertical edges of the back 2 opening forward the front 4 is provided at each of its vertical edges with a channel 14 opening rearward.
- 15 The above described channel members are all constructed substantially alike and they are preferably formed of a single piece of sheet metal bent into substantially U-shape 15 to form the channel and thence 25 bent back upon itself as at 16 to extend over the edge of the member to which it is attached and is thence bent at right angles and extends over the outside surface of the member as at 17. A packing strip 18 is 30 placed in the bottom of the channel to cushion the edge of the member which is inserted into the channel. This packing strip may be made of sponge, rubber, felt, or any 35 similar substance. The top and bottom edges of the front or table member 4 and all of the edges of the ends or stool members 5 are adapted to enter the channels and fit 40 against the packing 18 therein when the trunk is assembled as hereafter described.
- 45 The end members 5 are locked in assembled position by latches 19 fastened to the bottom 1, one near each respective end, which are adapted to engage the lips or detents 20 fastened to and projecting from the said ends 5. The top or bench member 3 is held in place by fastening it to the end members by key actuated locks 21 adapted to engage the detents 22 extending from the end members near their upper edges. The 50 locks 21 extend through the top member and are substantially flush with the outer surface thereof and have key slots for the insertion of keys 23 by which they are actuated. The front member 4 is retained in place by rearwardly extending prongs 24 at its lower edge which lie within the channels 12 and are engaged by the lower edges of the respective end members 5, the said lower edges of the end members being notched at 55 25 to receive the said prongs.

In practice the connected bottom and back members 1 and 2 are usually fastened permanently to the automobile preferably to a rack upon the back thereof or they might 60 be attached to one of the running boards.

It is not intended to use the back and bottom as articles of furniture although it is obvious that they also might be separable and provided with legs adapting them to be converted into additional tables or 70 benches. In assembling the trunk the front member with the legs folded is first placed with its lower edge in the channel 12 at the front edge of the bottom member. In this position the prongs 24 are extended a 75 short distance into the end channels 12 at the ends of the bottom members and the end members 5 with the legs folded are next placed in assembled position with their vertical edges in the respective channels 13 and 14 and their bottom edges in the end channels 12, the bottom edges engaging the prongs 24 at the notched portions 25, after these parts have been assembled the latches 19 are turned by reaching into the trunk 80 from the open top so that they engage the detents 20 on the ends 5. These latches afford a connection between the ends and the bottom and as the ends overlap the prongs 24 which extend from the front member 4 85 the front member is also retained and connected with the bottom.

The trunk is now in condition to receive such articles of camp equipment or luggage as are desired to be carried in it these being 90 entered through the open top of the trunk. After the trunk is packed the top member 3, which has the channel 11 extending entirely around its edge and opening downwardly, is placed in a position with the top edges 100 of the back, front and end members entering the said channel 11 and the locks 21 are turned by means of a key 23 to engage the detents 22 on the end members which holds the top in place. When the top is in place 105 all of the vertical members are rigidly held from spreading and the entire assembly is tightly closed to the exclusion of dust or moisture and cannot be opened without turning the locks 21 to release the top.

It will be noted that all of the channels and fastening means are so located on their respective members that they will not interfere in any way with the use of these members as articles of furniture. There 115 are no parts projecting from the surfaces of the members which are so used. Furthermore the absence of exterior connecting or fastening means affords a trunk of exceeding neatness and pleasing appearance. The fact that the only fastening means exposed when the trunk is closed and locked being the key slotted surface of the locks 21 which makes it practically impossible to tamper with any of the fastening means or to open the trunk without the proper key to fit the locks.

The modified means which connect the edges of the members illustrated in Figs. 10 and 11 enables dust and water tight joints 120

to be made without the use of the packing strip 18 described in the preferred structure. In both of these fastening means the edges of the vertical members such as the 5 front 4 are provided with grooves 26. In the structure shown in Fig. 10, which is intended to be used as a connection between the top 3 and the vertical members, a tongue 27 is provided to enter the groove 26 and 10 an outside flange 28 overlaps the outside surface of the vertical member causing water which might flow over the trunk to carry downward over the outside surface instead of entering the joint. The connection between 15 the bottom and the vertical members illustrated in Fig. 11 provides for a tongue 29 to extend upwardly into the groove 26 and no outside flange is necessary.

The outstanding features of this invention are the practicability and simplicity of the connecting means and locking devices. These are extremely efficacious in producing a tight but easily disconnected joint the case is not defaced by unsightly exterior 25 connecting devices and the surfaces of the different members are unobstructed for use.

I claim:

1. A camping trunk having, separable top, bottom and vertical sides, means for connecting all of said separable members, excepting one, to each other at the inside of the device and means for locking the said one member onto the other members from the outside of the device.
2. A camping trunk comprising, a bottom and vertical back member permanently joined together, a top and vertical front and end members separable from the bottom and back members and from each other, means 40 for fastening the front and end members to the bottom member at the inside of the device, and means for fastening the top member over the vertical members operable from the outside of the device.
3. A camping trunk having, a bottom, top, ends and front members which are separable from each other, means for fastening the end members to the bottom at the inside of the device, interengaging means 45 on the said front and end members to hold the front to the bottom, and means upon the top member actuated by a key from the outside of the device to lock the top to the sides.
4. A camping trunk having, a bottom,

ends, front and top, separable from each other and adapted to be used as articles of furniture, extensions upon the front engaged by the end members when assembled to retain the front in position, latches upon the bottom to engage the end members when assembled to fasten them to the bottom, and key actuated locks upon the top member to fasten the same to the end members when assembled.

5. A camping trunk comprising, a bottom and vertical back permanently fastened together, end, front and top members separable from the bottom and back and from each other, interengaging joining means at 70 the separable edges of said members, extensions on the front member engaged by the end members when assembled to retain the front member in position, latches upon the interior of the device to connect the end members with the bottom, and locks, key actuated from the outside of the device, to fasten the top to the end members.

6. A camping trunk comprising, a bottom and vertical back permanently fastened together and separable top, front and end members, channels upon the vertical edges of the back and upon the end and front edges of the bottom, channels upon the vertical edges of the front and channels upon the four edges of the top, said channels being adapted to receive edges of the various members when the device is assembled, extensions on the front engaged by the ends when assembled to retain the front in position, 80 latches at the inside of the device to fasten the ends of the bottom, and locks, key actuated from the outside of the device to fasten the top to the ends.

7. A camping trunk comprising, a bottom and vertical back permanently fastened together and separable top, front and end members, channels upon the vertical edges of the back and upon the end and front edges of the bottom, channels upon the vertical edges of the front and channels upon the four edges of the top, said channels being adapted to receive edges of the various members when the device is assembled, and means for detachably fastening said separable members to the back and bottom and to each other to form a trunk.

In testimony whereof I affix my signature.

JULES E. REBOURS.
